UNITED STATES PATENT OFFICE.

CHARLES L. CARMAN, OF CHICAGO, ILLINOIS.

CLUTCH.

SPECIFICATION forming part of Letters Patent No. 483,601, dated October 4, 1892.

Application filed January 26, 1892. Serial No. 419,259. (No model.)

To all whom it may concern:

Be it known that I, CHARLES L. CARMAN, of Chicago, in the county of Cook and State of Illinois, have invented certain new and useful 5 Improvements in Clutches; and I do hereby declare that the following is a full, clear, and exact description thereof, reference being had to the accompanying drawings, and to the letters of reference marked thereon, which form 10 a part of this specification.

This invention relates to clutches, and more particularly to that class known as "friction-clutches," and has for its object to provide in clutches of this description an increased frictional contact-surface without an undue increase in size, weight, or the number of parts, and also an increase of pressure on the contact-surfaces, whereby the efficiency of the clutch is materially increased.

20 To these ends the invention consists in certain novel features, which will first be described, and then particularly pointed out in the appended claims.

In the accompanying drawings, Figure 1 is 25 a sectional view of a clutch mechanism embodying my invention in one form. Fig. 2 is a sectional view of the same, taken on line 2 2 of Fig. 1. Fig. 3 is a section taken on line 3 3 of Fig. 2, showing toggles in plan view. 30 Fig. 4 is a sectional view illustrating a modification. Fig. 5 is a sectional view thereof, taken on line 5 5 of Fig. 4.

In the drawings, Figs. 1, 2, and 3 show the invention as embodied in one form, and also 35 show the same as applied to a structure wherein it is used for the purpose of connecting a loose pulley with its shaft. In this construction A represents the shaft, and B a loose pulley mounted thereon, a bushing a being interposed between the two in the usual manner. Upon the pulley B there is mounted a flat ring or annulus C, arranged in a plane perpendicular to the axis of rotation of the shaft and pulley. In the present instance 40 this annulus is shown as cast in one piece with the pulley, being united with the spokes b thereof. The free face of this annulus forms a flat radial fixed friction-surface c of annular form.

45 C' represents a second annulus parallel with the annulus C, rigidly connected with the pulley B and having a friction-surface c'

opposite and directly facing the surface c, with which it corresponds. As a desirable mode of connecting the annulus C' with the 55 pulley, it may be provided with a cylindric extension C², terminating in a flange c², by means of which it is secured to the outer margin of the annulus C by means of bolts b' or otherwise. Strengthening-ribs C³ extend 60 along the outside of the parts C' C² and serve to reinforce the same in an obvious manner.

The parts just described constitute one member of the clutch. The other member consists of the parts which will now be described.

D represents a hub secured on the shaft A by a key d or the like immediately adjacent to the pulley B. From this hub there extends radially outward a plurality of spokes D'. 70 Each of these spokes is provided at its free end with a sleeve or eye d', in which is mounted a pin D², parallel with the shaft A and projecting beyond the sleeve or eye d' in both directions, being secured therein by a set- 75 screw d² or other suitable means.

E E' are two rings located, respectively, opposite the annuli C C' and having on their outer faces friction-surfaces e e', which respectively coincide with and are adapted to 80 bear against the surfaces c c'. These rings are supported by the spokes D', the pins D² of which enter and fit loosely within apertures e² in said rings, which latter are desirably provided with bosses or hubs E², in which said 85 apertures are located. The rings are thus supported in proper position and are at the same time free to move toward and from each other. The rings E E' are provided with a suitable mechanism by which they may be 90 moved into contact with the friction-surfaces c c' or withdrawn from such contact. The mechanism preferred for this purpose is a toggle mechanism, and in the construction now under consideration is shown one form of construction which I have devised to accomplish 95 this end. In this construction the rings E E' are connected by toggle-links F and G to toggle-arms H, pivoted to a sleeve I, longitudinally movable on the shaft A. The link F is 100 desirably a two-part link of adjustable length and, as shown, consists of a part F', provided at one end with an eye f, by means of which it is pivoted between lugs e³ on the ring E, its

other end being threaded and screwing into one end of a right-and-left nut f' , the other end of which nut receives the reversely-threaded end of the other part F^2 of the link F . The other end of the part F^2 is provided with an eye f^2 , by means of which it is pivotally connected with the arm H and link G . A pivot pin or bolt F^3 , of any suitable construction, passes through the lugs e^3 and eye f and connects these parts, and a lock-nut f^3 on the part F^2 serves to lock the right-and-left nut f' in position after adjustment. The links G are in duplicate and are pivoted on opposite sides of a lug e^4 on the ring E' by means of a pivot pin or bolt G' , and the outer end of the arm H is bifurcated, forming forks h . These forks h fit on opposite sides of the eye f^2 and the links G fit outside of the said forks h , a pivot pin or bolt H' passing through all of these parts and pivotally connecting the same. The inner end of the arm H is provided with an eye or sleeve h' , whereby it is pivotally secured between lugs i on the sleeve I by means of a pivot pin or bolt H^2 . These parts just referred to are employed in multiple, being arranged equidistantly around the hub D , and so many groups thereof being employed as are found necessary or desirable. In practice it is preferred to employ a number equal 30 to the number of spokes D' , each group being arranged between two of the said spokes. The sleeve I is not in contact with the hub D , but extends loosely over the same and outward beyond it, bearing on the shaft at a point beyond the hub and being there contracted for this purpose. At the point where it bears on the shaft the inner surface of the sleeve is rounded off, as shown at i' , to permit a rocking of said sleeve relatively to said shaft on 40 the surface i' as a fulcrum. The sleeve is provided with an external annular groove i^2 in its periphery to receive a strap I' , to which is connected a lever i^3 , by means of which the sleeve I may be moved longitudinally of the shaft A in the usual manner. An annular plate J is secured to the outer face of the inner edge of the annulus C' and serves as a 45 dust-guard to prevent the access of dust to the interior mechanism of the clutch.

50 The operation of the clutch thus constructed is as follows: The parts of the second clutch member are assembled on the shaft and placed in proper position thereon, and the part $C' C^2$ of the first member is then secured in place 55 on the pulley. The nuts f' are then so turned as to adjust the toggle-links to the proper length to cause the rings $E E'$ to bear with their maximum pressure against the friction-surfaces $c c'$ when the arms H are radial and 60 the links $F G$ in a straight line with each other. It will be seen that when the sleeve I is moved into the position shown in full lines in Fig. 1 the two members of the clutch will be united by the frictional contact between the friction-surfaces $c e$ and $c' e'$, so that motion imparted to one of said members will be transmitted to the other. When the

sleeve is moved into the position shown in dotted lines in said figure, the meeting ends of the links $F G$ will be drawn downward and the rings $E E'$ will be drawn away from the surfaces $c c'$, thus severing the connection between the two members. During these movements of the rings they are guided and supported on the pins D^2 of the spokes D' , which serve, also, to cause them to rotate in unison with the hub D and shaft A . When the arms H are radial and the links $F G$ in line, the parts are locked against accidental displacement. The extent of the friction-surfaces of 80 the two members in contact with each other is very great and the durability of the clutch is increased to a corresponding extent.

The provision for permitting the sleeve I to rock on the shaft is for the purpose of equalizing any inequalities in the adjustment of the several adjustable links F . In practice it is found extremely difficult to adjust these several links to exactly the same extent, and by permitting the free end of the sleeve I to 90 vibrate freely laterally with relation to the shaft this end of the sleeve virtually centers itself relatively to the toggles when the latter are adjusted, thus insuring equality of action of the toggles even when the adjustment of 95 them is not exactly similar.

I do not wish to be understood as limiting myself strictly to the precise details of constructions just described, as various modifications may be made without departing from the principle of my invention. For instance, the annulus C , instead of being cast in one piece with the pulley B , may be made separate therefrom and connected therewith by screw-bolts or in any other suitable manner, 105 and this latter construction is of especial advantage when the invention is to be applied where there is a loose pulley already in position. Again, the annulus may be connected with the annulus C or pulley B in any other suitable way than that shown. Moreover, the particular mode of connecting the rings $E E'$ and hub D may be varied in many ways— 110 as, for instance, by having integral projections on the spokes or by having the projections on the rings instead of on the spokes. The invention also contemplates omitting portions of the rings $E E'$, or, in other words, 115 making the said rings in separate segments, and mechanism for positively moving the rings other than the toggle mechanism shown and described may be employed. The modifications are, however, obvious and need no detailed description here.

As an illustration of a structure modified 120 in detail but containing the essence of the invention, I have shown in Figs. 4 and 5 a shaft-coupling embodying my invention in a modified form. In this structure A and A' are the shafts to be coupled, one member being secured on one of the shafts and the other member being secured on the other shaft. The part B is a radial disk with suitable strengthening ribs, having the annulus C and part C^2 in one

piece therewith, and the annulus C' is bolted to the edge of the part C², as shown. The spokes D' are hollow, being open at one side, and therefore U-shaped in cross-section, and 5 serve to connect the hub D with a rim D³, provided at each spoke with an aperture d³. The annuli E E' are provided with inwardly-projecting lugs e⁵, which rest upon the rim D³ between lugs e⁶ on the periphery of said 10 rim and serve to center and support the annuli while permitting them to slide toward and from each other. The links F and G are non-adjustable, provision for adjustment being made by constructing the arms H in two 15 parts H² H³, having threaded connection, so that the length of the arms may be varied as desired. The arms H are located within the hollow spokes D' and extend through apertures d³. The lugs i of the sleeve I fit within 20 the side walls of the hollow spokes D' and cause said sleeve to rotate along with said spokes and hub D. The sleeve I fits and slides on the hub D, provision for rocking being made, as shown by the contracted portion of 25 the sleeve only bearing upon said hub. It will be observed that in this construction the parts are so adjusted that the links F G are not in line with each other when the clutch is set, thus providing for normal wear without 30 the necessity of frequent adjustment of the arms H. Thus lateral adjustment or play of the sleeve I relatively to the shaft is provided as in the construction first described.

It will be understood, of course, that the 35 modified features shown in Figs. 4 and 5 and just described are equally applicable to a clutch for connecting a loose pulley to a shaft, as in the construction first described, and conversely the construction shown in Figs. 1, 2, 40 and 3 is adapted for use as a shaft-coupling.

What I claim is—

1. A friction-clutch comprising two members, one provided with two opposite fixed friction-surfaces radial to the axis of rotation 45 and the other provided with two movable parts having friction-surfaces located, respectively, opposite to and parallel with said fixed friction-surfaces, and mechanism for positively actuating said movable parts away 50 from each other in the line of the axis of rotation to engage the friction-surfaces, substantially as described.

2. A friction-clutch comprising two members, one provided with two opposite fixed friction-surfaces radial to the axis of rotation and the other provided with two movable rings located, respectively, opposite to and parallel with said friction-surfaces, and toggle mechanism for actuating said rings away from 55 each other in the line of the axis of rotation, substantially as described.

3. A friction-clutch comprising two members, one provided with two annuli, one of which is detachable, said annuli having opposite friction-surfaces radial to the axis of 60 rotation, the other member being provided

with two movable rings located between said friction-surfaces and respectively opposite to and parallel with the same, and mechanism for positively actuating said rings in opposite directions in the line of the axis of rotation, substantially as described. 70

4. A friction-clutch comprising two members, one provided with two opposite fixed friction-surfaces radial to the axis of rotation 75 and the other provided with two movable rings located, respectively, opposite to and parallel with said friction-surfaces, and a plurality of toggle mechanisms for actuating said rings away from each other in the line 80 of the axis of rotation, one of the members of each toggle mechanism being adjustable, substantially as described.

5. A friction-clutch comprising two members, one provided with two opposite fixed 85 friction-surfaces radial to the axis of rotation and the other provided with two movable rings located, respectively, opposite to and parallel with said friction-surfaces, and a plurality of toggle mechanisms each comprising 90 links pivoted, respectively, to the rings and to each other, one of said links being a two-part link of adjustable length, an arm pivoted at one of its ends to the links at their point of connection, and a longitudinally-movable 95 sleeve to which the other end of said arm is pivoted, substantially as described.

6. The combination, with a shaft, of a clutch one member of which is provided with two opposite fixed radial friction-surfaces, the 100 other member being provided with two movable rings located, respectively, opposite to and parallel with said friction-surfaces, a plurality of toggle mechanisms each comprising toggle-links and a toggle-arm, and a sleeve 105 connected with the said toggle-arm and being longitudinally movable on the shaft and free of contact therewith at its point of connection with said arms, substantially as described. 110

7. The combination, with a shaft, of a clutch one member of which is normally disconnected from said shaft and is provided with two opposite fixed radial friction-surfaces, the other member comprising a body fixed on 115 the shaft and having guiding and supporting devices, two movable parts mounted on said guiding and supporting devices and rotated thereby, and mechanism for actuating said movable parts away from each other in the line of the axis of rotation to engage the friction-surfaces thereof with the fixed friction-surfaces, substantially as and for the purpose set forth.

In testimony that I claim the foregoing as 125 my invention I affix my signature in presence of two witnesses.

CHARLES L. CARMAN.
